UNITED STATES PATENT OFFICE

156,408

CAP

Alfred Cohn, Milwaukee, Wis.

Application April 30, 1949, Serial No. 2,357

Term of patent 7 years

(Cl. D3—13)

To all whom it may concern:

Be it known, that I, Alfred Cohn, a citizen of the United States of America, residing at Milwaukee, in the county of Milwaukee and State of Wisconsin, have invented a new, original, and ornamental Design for a Cap, of which the following is a specification, reference being had to the accompanying drawing, forming a part thereof.

In the drawing:

Fig. 1 is a top view of a cap, showing my new design;

Fig. 2 is a side elevation of the cap shown in Fig. 1; and

Fig. 3 is a front view of the same cap.

I claim:

The ornamental design for a cap, substantially as shown.

ALFRED COHN.
